(57) **CLAIM**

The ornamental design for a divider for a storage container, as shown and described.

DESCRIPTION

FIG. 1 is a front isometric view of a divider for storage container showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a sectional view thereof taken along line 7-7 of FIG. 3;

FIG. 8 is a top view thereof;

FIG. 9 is a bottom view thereof; and,

FIG. 10 is a section view thereof taken along line 10-10 of FIG. 3.

The dot-dash broken lines throughout the drawings represent a boundary of the claimed design. The dash-dash broken lines throughout the drawing figures depict portions of the divider for a storage container that form no part of the claimed design. The broken lines and unshaded surfaces bounded by broken lines form no part of the claimed design.
